UNITED STATES PATENT OFFICE.

CHRIST JOHNSON, OF SHELBY, MONTANA.

FIREMAN'S AX.

Application filed March 6, 1925. Serial No. 13,480.

To all whom it may concern:

Be it known that I, CHRIST JOHNSON, a citizen of the United States, residing at Shelby, in the county of Toole and State of Montana, have invented certain new and useful Improvements in Firemen's Axes, of which the following is a specification.

This invention relates to an improved fireman's ax and seeks, among other objects, 10 to provide an ax which will fully meet the peculiar requirements of a fireman as regards a tool of this character.

The invention seeks, as a further object, to provide an ax not only having a bit but 15 also having a pick point, either of which may be used with equal facility.

And the invention seeks, as a still further object, to provide an ax wherein the bit will be in the shape of a hook which may be engaged over a beam or the like so that the ax may be used to assist a fireman in climbing while, when the ax is not in use, the hook may be engaged over the arm or over a belt of the fireman so that the ax may be 25 readily carried.

Other and incidental objects will appear hereinafter.

In the accompanying drawings:

Figure 1 is a side elevation of my improved fireman's ax;

Fig. 2 is a sectional view on the line 2-2 of Fig. 1, looking in the direction indicated by the arrows; and

Fig. 3 is a transverse sectional view on the line 3-3 of Fig. 1, looking in the direction indicated by the arrows.

In carrying the invention into effect, the ax is formed with an elongated eye 10 which, as illustrated in Fig. 2, is elliptical in cross-section. The eye 10 receives an appropriate handle 11. Extending from the forward side of the eye at its outer end is a pick point 12 rectangular in cross-section. The pick point is preferably straight and gradually tapers to a sharp piercing point. Located at the rear side of the eye 10 is a bit 13 which, as shown in Fig. 3, is provided with flat side faces converging to define an arcuate cutting edge 14, and extending from 50 the upper end of the bit is a straight shank 15 integral with the outer end of the eye at its rear side. As shown in Fig. 2, the

shank 15 of the bit extends in alinement with the pick point 12 and, as will be observed, the flat side faces of the shank converge at the same angle as the flat side faces of the pick point. Furthermore, the side faces of the shank 15 merge with the angular side faces of the bit 13 so that the upper end of the bit and the shank thus define an elongated wedge well adapted to pry apart boards or timbers. Formed on the bit at its lower end is a rearwardly directed toe 16 tapered toward its free end and provided with a terminal rounded button 17. The toe 60 may, of course, be used as a pry and it is now to be noted that the bit 13, shank 15, and toe 16 form a hook which may be readily engaged over a timber or the like so that the ax may be employed to assist a fireman 65 in climbing. Furthermore, said hook may be engaged over the belt of a fireman and the ax thus conveniently carried. The bit extends parallel to the axis of the eye and preferably said bit is longer than the eye 70 while the toe curves upwardly and inwardly toward the eye.

Having thus described the invention, what I claim is:

1. A tool comprising a shank having an eye at one end and a bit at the opposite end, both the bit and the eye extending laterally from the same side of the shank in parallel relation, and the bit having a projection at its free end in the plane of the shank and extending toward the eye and curving toward the eye and shank and terminating in an enlargement.

2. In a fireman's ax, the combination of an eye provided at one side thereof with a prong extending laterally from the outer end of the eye and at its opposite side with a laterally directed shank extending laterally from the outer end of the eye in alinement with said prong, the shank being formed at its outer end with a depending bit longer than the eye and provided at its lower end with a rearwardly directed toe curving upwardly toward the eye and cooperating with the bit and shank to define 100 a hook.

In testimony whereof I affix my signature,

CHRIST JOHNSON. [L. S.]
